United States Patent Office.

PATRICK H. COYLE, OF NEWARK, NEW JERSEY.

Letters Patent No. 91,523, dated June 22, 1869.

IMPROVEMENT IN STEAM-GENERATOR-FLUE BRUSHES.

The Schedule referred to in these Letters Patent and making part of the same.

Be it known that I, PATRICK H. COYLE, of the city of Newark, county of Essex, and State of New Jersey, have invented a new and useful Improvement in Boiler-Flue Brushes; and I do hereby declare that the following, taken in connection with the drawings, which accompany and form part of this specification, is a description of my invention, sufficient to enable those skilled in the art to practise it.

The object of my invention is the construction of a guard for boiler-flue brushes, by means of which the brush can be readily drawn or guided back into the flue after having been pushed through the same in cleaning.

In the accompanying drawings—

Figure 1 represents a longitudinal section of a brush

with my invention attached, in which M M M M are the braces which form the guard, and which are attached to the body of the brush at R R, and to a socket, enclosing the handle of the same, at P P.

Having thus described my invention,

What I claim as new, and desire to secure by Letters Patent, is—

The combination, with the boiler-flue brushes, of a guard to guide the brush back into the flue after having been pushed through, substantially as set forth.

PATRICK H. COYLE.
